HEEL CLAMPING DEVICE

Meldon A. Shaffner, Milwaukee, Wis.

Application April 15, 1933, Serial No. 666,275

5 Claims. (Cl. 12—125)

This invention appertains to the manufacture of shoes and more particularly to a novel clamp for holding shoe heels on their seats incident to the gluing of the heels in place and the handling of the shoe during certain other shoe manufacturing steps.

Many attempts have been made to produce a clamp for holding a French heel on its seat (see my pending application filed April 18, 1932, Serial No. 605,915 now Patent No. 1,938,196 of Dec. 5, 1933). All of these clamps with which I am familiar are objectionable, in that the pressure is not evenly distributed to the heel due to the shape of the heel, and the heel tends to cant or twist on its seat resulting in an unsatisfactory bond between the heel and seat. Further, with all of these clamps, the front edge of the heel is not firmly held against the breast of the sole and in fact, the clamp tends to pull the heel away from the breast of the sole.

It is therefore one of the salient features of my invention to provide a novel clamp which will effectively hold the heel on its seat and evenly distribute the pressure over the entire heel seat and firmly hold the heel against the breast of the sole.

A further important object of my invention is to provide a compensating heel clamp, which is so constructed that the clamp is permitted to give as pressure is applied to the heel and last, thereby allowing the effective distribution of the thrust to the heel seat.

A further important object of my invention is the provision of a novel shoe heel clamp of a substantially C-shape having an adjustable screw for engaging the last and a foot for engaging the tread or lift of the heel, the lower part of the clamp closely conforming to the configuration of the rear of the heel and being provided with a pivot joint, whereby upon the tightening of the clamping screw the foot will be brought into pressure contact with the heel and whereby the clamp will give at its joint permitting forward thrust at the joint on the heel which thrust in combination with the thrust on the tread of the heel holds the heel firmly on its heel seat with a forward thrust, so that the front edge of the heel will be held into intimate contact with the breast of the sole.

A further object of my invention is the provision of the use of a short length of rubber tubing or hose for enclosing the clamp at its joint, the inherent resiliency of the tubing tending to hold the sections of the clamp in proper place and acting as a buffer or guard for engaging the ex-

terior face of the heel to prevent marring of the surface, the tubing being movable around the joint so that as one part thereof becomes soiled, another part thereof can be brought into position for engaging the heel.

A further object of my invention is the provision of a removable pin holding the sections of the clamp together at their pivot point, the pin being held in place by the rubber tubing or sleeve, the use of the pin permitting the free removal of the clamping part, when it is desired to renew the rubber tubing, when the same becomes worn.

A still further object of my invention is to provide an improved clamp of the above character, which will be durable and efficient in use, one which can be placed upon the market at a reasonable cost.

With these and other objects in view, the invention consists in the novel construction, arrangement and formation of parts, as will be 20 hereinafter more specifically described, claimed and illustrated in the accompanying drawing, in which:—

Figure 1 is a side elevation of my improved clamp showing the same applied to a shoe and last and just prior to the final tightening thereof, the rubber tubing for the joint being shown partially broken away and in section.

Figure 2 is a fragmentary detail section of the lower end of the clamp showing the pivot joint 30 with its loose pivot pin.

Figures 3, 4 and 5 illustrate slightly modified forms of devices for engaging the heel.

Referring to the drawing in detail, wherein similar reference characters designate the corresponding parts throughout the several views, the letter A generally indicates my improved clamp for holding a French heel 5 on a shoe 6, being fabricated on a conventional last 7. The shoe is manufactured in accordance with the usual method and my improved clamping device A is utilized for effectively holding the heel 5 on its heel seat and firmly against the breast of the sole.

As clearly shown in Figure 1, my improved clamp A is of a substantially C-shape and the upper end thereof is provided with a substantially vertically disposed threaded boss or sleeve 10 in which is adjustably mounted the clamping screw 11 having the nubbed head 12 on its upper end and the smooth button 13 on its lower end for engaging the last. The lower end of the C-shaped body portion 14 of the clamp receives the pivoted angle foot 15, the horizontal portion 16 of which carries means 17 for engaging the tread or lift of the heel 5. The meeting ends of the

angle foot 15 and the body 14 are provided with mating overlapping pivot ears 18 and these ears are provided with registering openings for the reception of a loose and freely removable pivot pin 19.

By the construction so far, it is to be noted that the lower end of the body 14 of the clamp and the upper end of the angle foot 15 closely conform to the curvature of the outer surface of the heel and 10 that the foot is permitted to give or swing as the clamp is adjusted.

In order to hold the angle foot against free unhindered swinging movement, a rubber sleeve 20 is placed over the pivoted joint and this rubber sleeve may be in the nature of a short length of 15 rubber tubing or hose. The same can be placed in position in the following way, namely; the pin 19 is removed and the rubber sleeve is slipped on the lower end of the body until the same rides 20 past the ear formed on the lower end of the body after which the angle foot is placed into position and the pin is disposed through the registering openings, after which the rubber sleeve is slipped down in the position shown in Figure 1 of the 25 drawing. When the rubber sleeve becomes worn, it is merely necessary to push up the same, as shown in dotted lines in Figure 1, remove the pin, slip off the sleeve and place a new length in position.

Particular stress is laid on the following action 30 of the clamp and the same is applied to the shoe and last as shown in Figure 1 of the drawing, after which the screw clamp is tightened. This causes a drawing action between the button 13 of the 35 screw and the angle foot and as this drawing action increases, the clamp breaks at its joint inwardly and moves into forcible contact with the heel resulting in a forward movement to hold the heel against the breast of the sole and an inward 40 thrust, so as to evenly distribute the pressure over the entire heel seat.

In practice, it has been found that this clamp 45 effectively accomplishes the purpose intended and particular stress is laid on the fact that two lines of force are exerted on the heel with the adjustment of a single screw.

In Figure 3 I have shown a slightly modified 50 form of means for engaging the lift of the heel and as shown the arm 16 of the lower member 15 is provided with an integral foot 25 for engaging the lift of the heel.

In Figure 4, I have shown a further modified 55 form of means for engaging the heel lift. In this form I provide a tapered pin 26 which can extend through the arm 16 and can be held in place by having its lower end upset, as at 27.

In Figure 5, I have shown a still further modified 60 form of means for engaging the lift of the heel. In this particular form a tapered projection 28 is formed directly on the outer end of the arm 16 and this projection can be formed in the middle of a cup-shaped recess 29, which limits the penetration of the projection into the heel lift.

Obviously the integral foot and its associated part 16 may in some cases be pivoted to the lower member 15.

Changes in details may be made without departing from the spirit or the scope of this invention, but what I claim as new is:—

1. A shoe heel clamp comprising a body of a substantially C-shape, a pivoted angle foot connected to the lower end of the body having a forward projecting portion for engaging the lift of the heel to be clamped, the pivot for the angle foot being disposed in rear of the heel to be clamped, the angle foot and lower end of the body closely following the curvature of the heel, and an adjusting screw carried by the upper end of the body.

2. A shoe heel clamp comprising a body of a substantially C-shape, an angle foot pivotally connected to the lower end of the body, the pivot for the angle foot being disposed in rear of the heel to be clamped, a clamping screw carried by the upper end of the body, and means normally tending to hold the angle foot against swinging movement relative to the body.

3. A shoe heel clamp comprising a substantially C-shape body portion, an angle foot pivotally connected to the lower end of the body, the pivot for the angle foot being disposed in rear of the heel closely conforming to the rear of the shoe heel being clamped, and an adjusting screw carried by the upper end of the body, movement of the screw tending to force the angle foot into engagement with the lower face of the heel and the lower end of the body into engagement with an intermediate portion of the heel.

4. A shoe heel clamp comprising a substantially C-shaped body portion, an angle foot pivotally connected to the lower end of the body portion, the pivot for the angle foot being disposed in rear of the heel to be clamped, the angle foot and lower end of the body portion closely conforming to the exterior configuration of the rear of the heel being clamped, and a short length of rubber tubing housing said pivotal connection of the body and foot for engaging the rear face of the heel.

5. A shoe heel clamp comprising a substantially C-shaped body portion, an adjusting screw carried by the upper end of the body portion, an angle-shaped foot disposed below the body portion, the meeting ends of the body portion and foot being disposed in rear of the heel to be clamped and provided with overlapping ears having registering openings, a pivot pin removably fitted in the openings of the ears, and a short length of tubing slipped over the lower end of the body portion and the upper end of the foot enclosing said ears whereby to prevent loss of the pivot pin and for abutting engagement with an intermediate portion of the heel being clamped.

MELDON A. SHAFFNER.
